UNITED STATES PATENT OFFICE.

WALTER SCOLES, OF LONDON, ENGLAND, ASSIGNOR TO THE FIRM OF J. K. FARRELL, OF LONDON, ENGLAND.

DESIGN FOR A TOY.

46,069.

Specification for Design.

Patented July 7, 1914.

Application filed August 4, 1913. Serial No. 782,956. Term of patent 3½ years.

To all whom it may concern:

Be it known that I, WALTER SCOLES, a subject of the King of Great Britain, residing at London, England, have invented a new, original, and ornamental Design for a Toy, of which the following is a specification, reference being made to the accompanying drawing, forming part thereof.

I claim:

The ornamental design for a toy as shown.
WALTER SCOLES.
